CLAIM

The ornamental design for a plunger boot, as shown and described.

DESCRIPTION

FIG. 1 is a side elevation view showing my new design for a plunger boot:

FIG. 2 is a top view of FIG. 1; and,
FIG. 3 is a bottom view of FIG. 1.

The broken lines in the figures illustrate portions of the plunger boot that form no part of the claimed design.

1 Claim, 3 Drawing Sheets(56)
